CLAIM

The ornamental design for a mobile phone case, as shown and described.

DESCRIPTION

FIG. 1 is a perspective view showing my new design for a mobile phone case;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a perspective view thereof, shown in an alternate configuration; and,

FIG. 9 is an exploded perspective view thereof.

The broken lines in the drawings depict portions of the mobile phone case that form no part of the claimed design.

1 Claim, 8 Drawing Sheets
